DESIGN FOR AN ASH TRAY

Harry S. Stronach, Oak Park, Ill.

Application March 22, 1944, Serial No. 112,995

Term of patent 3½ years

(Cl. D85—2)

To all whom it may concern:

Be it known that I, Harry S. Stronach, a citizen of the United States, residing at Oak Park, in the county of Cook and State of Illinois, have invented a new, original, and ornamental Design for an Ash Tray, of which the following is a specification, reference being had to the accompanying drawing, forming a part thereof.

In the drawing:

I claim:

The ornamental design for an ash tray, as shown.

HARRY S. STRONACH.
